UNITED STATES PATENT OFFICE.

LOUISE H. BOCH, OF NEW YORK, N. Y.

KIT BAG.

Application filed May 8, 1925. Serial No. 28,764.

This invention relates to improvements in bags adapted for use as sewing kits, vanity bags and the like.

The invention will be apparent from the following specification when read in connection with the accompanying drawings in which—

Fig. 1 is a perspective view of a bag embodying the invention and showing it in open position;

Fig. 2 is a similar view showing the bag partly closed;

Fig. 3 is a cross-sectional view of the open bag.

Fig. 4 is a diagram of the means for closing the bag.

Referring in detail to the drawings, the kit comprises an outer fabric bag 10 to which is sewed a fabric bottom 12. A line of stitching 14 along the upper edge of the bag 10 defines a hem 16 within which is located a pair of draw strings 18 the ends 20 of which emerge from openings 22 at diametrically opposite points.

An interlining 24 is stitched to the bottom of the bag and at various points lines of stitching such as indicated at 26 are made so as to form pockets between the interlining and the side portion 10 of the bag, these being adapted to accommodate sewing articles such as spools of thread, thimbles and the like. In some instances, I may sew a pin cushion indicated diagrammatically at 28 to the bottom 30 of the interlining.

The pocket indicated at 32 in the drawings is formed with an overhanging flap 34 the upper edge of the pocket being at the point indicated at 36. As thus arranged, the pocket is more or less of a concealed one and access can only be had thereto by puckering the material as illustrated in Fig. 1 so as to lift

the flap 34 above the edge 36. Extending around the upper marginal edge of the interlining 24 is formed a hem 38 within which is located a pair of draw strings 40. These draw strings leave the interlining hem at points which are diametrically opposite each other and adjacent the openings 22 in the outer portion of the bag. By pulling the ends 44 and 20 of the respective draw strings 40 and 18 the upper portions of both the bag and the interlining will be puckered or collapsed and thus close both the bag and the space for pockets between the bag and the interlining and thereby preclude the possibility of articles falling either from the interior of the bag or from the pockets which it will be remembered are formed between the outer wall of the bag and the interlining. The draw string arrangement in effect may be said to form a duplex closing means or a double lock.

The bag may be made up in silk or various textile fabrics or of fine grades of hides such as suede, sheep skin, pin seal, and so forth.

Though I have described in detail the specific construction of the embodiment of the invention illustrated, it is not to be construed that I am limited thereto as various changes and substitution of equivalents may be made without departing from the invention as defined in the appended claim.

What I claim is:—

An article of manufacture comprising a bag having an inner lining secured to the bag at spaced intervals to form pockets and draw strings at the top of the bag and at the top of the lining respectively adapted to simultaneously collapse the bag and said lining.

In witness whereof, I have hereunto signed my name.

LOUISE H. BOCH.
